ATTACHMENT FOR BOX-COVERING MACHINES

Martin V. Silby, New York, N. Y.

Application December 5, 1947, Serial No. 789,877

7 Claims. (Cl. 93—54.2)

1

The invention relates to attachments for box-covering machines of the type described in U. S. Patent No. 691,329, issued January 14, 1902, to Smith.

The general object of the invention is to provide a novel and practical attachment for a machine of this type for the purpose of adapting the machine to operate to cover a box shell which is shaped externally like a truncated pyramid and internally like a parallelopiped.

A further object of the invention is to provide improved means in such an attachment whereby the corner-lapping tabs usually provided on certain side-wall-forming parts of cruciform cover blanks may be accurately and positively affixed to the outer side-wall corners of shells of the shape described above.

In the drawings:

Fig. 1 is a partly erased top plan view of those parts of a box-covering machine of the type described in the cited patent which engage box shells and cover blanks during a box-covering operation, and shows my attachment applied thereto.

Fig. 2 is an elevational view projected from Fig. 1. Many parts shown in Fig. 1 are here omitted for clarity, as the particular purpose of Fig. 2 is to illustrate the vertical positional relationship of several essential elements. Fig. 2 illustrates that stage in a box-covering operation, wherein the shell involved is as described in the preamble hereto, which immediately follows the affixing to the shell of the corner-lapping tabs of side-wall-forming parts of the cover blank: this stage of the process is illustrated in solid lines; the stage relating to the actual affixing of the corner-lapping tabs is shown schematically in the same figure by dotted lines.

Fig. 3 is a lengthwise view of one of four improved rollers which, in my attachment, are substituted for the four rollers ordinarily provided in a machine of the type described in the cited patent for the purpose of folding upward and affixing to the side-walls of the shell the four side-wall-forming parts of cruciform cover blanks.

Fig. 4 is a partly sectional vertical detail illustrating a stage in a box-covering operation, wherein the shell involved is as described in the preamble hereto, such stage being that almost immediately following the stage illustrated in Fig. 2 in solid lines.

Figs. 5 and 6, both also partly sectional vertical details, illustrate two successive stages of the box-covering operation wherein the shell is as described above.

Fig. 7 is a perspective view, from above, of a corner-stayed, preformed box shell shaped externally like a truncated pyramid and internally like a parallelopiped. The near corner of the

2

shell has been torn away so that the side-wall structure may be clearly seen. Dotted lines indicate the omitted corner of the shell.

Fig. 8 is a fragmentary perspective view of a corner of a cover blank suited for covering the shell of Fig. 7, showing one side-wall-forming part of said cover blank folded to correspond to the initial fold resulting from an operation of the machine with my attachment applied thereto.

10 In this figure one corner-lapping tab of the folded side-wall-forming part of the blank is also seen to have been folded into a plane corresponding to that actually assumed, with respect to the related side-wall-forming part, as a result of the second operation of the machine in covering such a shell as described above.

Fig. 9 is a plan view of the cover blank of Fig. 8, showing in dotted lines the several bend- or fold-lines.

20 Machines of the type described in the cited patent are adapted to cover rectangular box shells, i. e., shells which are parallelopipeds. Parts of such a machine are shown in Figs. 1, 2, 4, 5, and 6.

25 Preparatory to operating the machine to apply the usual type of cruciform cover blank to a rectangular box shell, the shell is placed, usually by hand, bottom-downward on the rectangular central portion of the flat cruciform blank, the latter having adhesive coating on its upper surface, i. e., the surface which is to be bonded to the shell itself in the box-covering operation.

The shell, with the flat blank adhering to its bottom external surface, is then placed upwardly 30 against a block, such as 11 in Figs. 2, 4, 5, and 6, fixed horizontally at the lower end of a vertically disposed plunger, such as 12 in Fig. 2, the block 11 having the shape and approximate dimensions of the inside of the shell and forming temporarily 35 a core therefor. The plunger 12 does not appear in Fig. 1, and is but sketchily shown in Fig. 2; however, the plunger structure is fully illustrated in the cited patent, and is also well known in the art.

40 Somewhat beneath the plunger 12 is another coaxial plunger, such as 13 in Fig. 2, having at its upper end a horizontally disposed plate, such as 14 in Figs. 2, 4, 5, and 6. When the machine is set in operation the plunger 12 descends, carrying the block, shell, and cover blank with it; when the under surface of the cover blank engages the upper surface of the plate 14 the two plungers then descend as a unit with the plate, cover blank, shell, and block between them. Obviously the two plungers and the block and plate serve together as a means for positively holding the box-forming elements in proper position during the box-covering operation.

45 The cover blank and the shell are carried down 50 between two opposing horizontally disposed roll-

ers which operate to engage and to fold upwardly an opposing pair of the four outwardly extending side-wall-forming parts of the cruciform cover blank—usually being a pair provided with corner-lapping tabs—and to affix these parts to the outside of two opposing vertical side-walls of the rectangular shell.

As the machine, modified by my attachment, is specially adapted to the covering of box shells not having external vertical side-walls, but external sloping side-walls, I substitute for the usual rollers, mentioned above, two modified rollers 15 and 16 (see Figs. 1, 2, and 3). My modified rollers 15 and 16 are more particularly described below.

As a rule the cover blank for a rectangular box shell is provided with a pair of side-wall-forming parts, oppositely disposed, each part having at either edge tabs designed to be folded with respect to the side-wall-forming part itself and so to lap around the corner of the shell; this follows common practice, of course, the purpose being to provide a cover for the finished box which is nowhere interrupted so as to expose part of the shell, as, for example, at the arris of two adjacent side-walls. Such corner-lapping tabs are first folded around the side-wall corners of the shell and affixed to parts of the outside of side-walls of the shell adjacent to the first pair of side-walls of the shell to which the first two side-wall-forming parts of the blank are affixed; when, in the continuous operation, the second pair of side-wall-forming parts of the cover blank are affixed to the shell these parts overlap the corner-lapping tabs; and no part of the arris of any side-wall corner of the shell is exposed in the finished box. Thus it will be clear that the affixing of the corner-lapping tabs is a proper second function of the box-covering machine.

Thus, the machine of the type described is provided with means, positioned beneath the pair of opposing rollers mentioned above, for engaging, folding, and affixing the corner-lapping tabs of the first pair of side-wall-forming parts of the blank immediately after such parts have been affixed to the shell. Such means, usually metal fingers (not illustrated), are mounted upon two opposing, horizontally disposed bars, such as 17 and 18 in Fig. 1 (bar 18 is also seen in Fig. 2). These bars, peculiar to machines of this type, are positioned beneath and parallel to the rollers mentioned above. Means which need not be described herein, and which are well-known in the art, operate to bring these opposing bars toward each other immediately after the box-forming elements have passed between the above-mentioned pair of rollers—when, it will be understood, two opposite side-wall-forming parts of the blank have been affixed to two opposite side-walls of the shell itself—for the purpose of engaging, folding, and affixing, by means of the metal fingers, abovementioned, the corner-lapping tabs of the side-wall-forming parts previously affixed to the shell.

In a machine of this type, modified by application thereto of my attachment, I substitute for the metal fingers means better suited to the somewhat unusual shape of the shell involved. Such means are described subsequently. The bars, however, and means for actuating them, are not modified.

Continuing now with the operation of the unmodified machine in covering a rectangular box shell: After the corner-lapping tabs have been

folded and affixed, the continuing descent of the plungers carries the box-forming elements between another pair of opposing, horizontally disposed rollers, similar to the first mentioned pair, but set at 90° thereto. The second pair of rollers operates to fold upwardly the remaining two side-wall-forming parts of the cover blank and to affix these parts to the other two side-walls of the shell, and also against, in part, the tabs affixed previously to these lastnamed side-walls of the shell.

In my attachment I substitute for these last two rollers, as for the first mentioned, a pair of modified rollers suited to shells of the shape described in the preamble hereto. These modified rollers are designated 19 and 20 in Figs. 1 and 2; roller 19 appears also in Figs. 4, 5, and 6. The four modified rollers substituted in my attachment for the usual rollers provided on such machines, are more particularly described subsequently.

I have described the operation of the machine in covering a rectangular box shell to that stage where all side-wall-forming parts of the cruciform cover blank have been affixed to the four side-walls of the shell. At this stage the box is externally covered; but if, as is customary, the cover blank is designed to cover not only the outside of the side-walls of the shell, but also the top edges of the side-walls and the inside surfaces thereof, a margin of each side-wall-forming part of the cover blank projects upward beyond the top edge of its related side-wall.

The next operation of the machine involves so-called edge (i. e., margin, of the side-wall-forming part of the cover blank) tuck-in fingers (cf. U. S. Patent No. 753,524, issued March 1, 1904, to Smith) or turn-in fingers (cf. U. S. Patent No. 1,424,316, issued August 1, 1922, to Morrison).

These fingers, their various designs, and their operation are well-known in the art. Briefly, the edge tuck-in, or turn-in, fingers move centripetally with respect to the box-forming elements during an interval in the box-covering operation wherein the block is temporarily retracted upwardly and so withdrawn from the shell, the latter being then supported by the plate, and engage and fold inwardly the four upstanding margins or edges of the four side-wall-forming parts of the cover blank; next, these fingers are retracted; and then the block and plate are again moved toward each other, effecting re-entry of the block into the shell and the folding down and affixing of the edges or margins of the side-wall-forming parts to the inner surfaces of the side-walls of the shell.

Fig. 1 shows four edge tuck-in, or turn-in, fingers, 21, 22, 23, and 24.

After operation of these fingers and the re-entry of the block into the shell the box is complete. It is next automatically ejected from the machine, which is then ready for another box-covering operation.

To facilitate understanding of the attachment of the present invention I now describe more particularly the structure and shape of the type of shell and cover blank relating to the type of box to be covered by the machine when modified by the attachment.

First, it may be mentioned, the machine operates only to cover a box shell and not to form the same during a box-covering operation. Thus the shell, whether of the rectangular shape usually seen, or of the type having the special shape

described in the preamble hereto, is ordinarily performed by hand before the covering operation, and, further, is customarily corner-stayed with stays independent of the cover blank, which, necessarily, as is obvious, serves as a stay as well as an ornamental cover; and as a reinforcement for any stays previously applied to the shell.

In Fig. 7 I show, in perspective, a typical, preformed, corner-stayed shell having the external shape of a truncated pyramid and the internal shape of a parallelopiped. I designate the shell, as a whole, by the index S. The visible corner stays are designated as 25, 25, 25. The shell is formed from a flat cruciform blank, as the figure clearly shows. The side-wall forming parts of the shell blank are folded upwardly on the four sides of a rectangular central portion 26, the bottom of which, in preparation for a covering operation, is bonded to the upper surface of a like-shaped rectangular central portion of a cruciform cover blank (see below). The first fold of each side-wall-forming part of the shell blank is more than 90°, so that the parts are not vertical, but sloping. Each side-wall-forming part is again folded, on a line parallel to its first fold-line, so that the shell shape shown in Fig. 7 results. The marginal cutting and scoring of fold-lines of the shell blank is usually a machine operation while the actual folding is often, though, of course, not necessarily, manual. The sloping corners of the sloping external side-walls—the side-walls giving the pyramidal shape to the outside of the shell—may be stayed by apparatus such as is described in my co-pending application in the United States Patent Office bearing Serial Number 789,879, and filed December 5, 1947, and covering a box-stay machine. This application also describes the structure of a shell having sloping outer walls and vertical inner walls.

To facilitate further reference to the shell S, I designate any sloping outer side-wall as 27, any vertical inner side-wall as 28, and any sloping outside side-wall corner as 29.

The shell S, of course, may be of any suitable material, usually cardboard.

Figs. 8 and 9 illustrate a cover blank, for instance, of paper, suited for a shell such as is shown in Fig. 7. The flat cover blank of Fig. 9 is designated as a whole by the index B. The rectangular central portion of the cover blank B is designated 30; in preparation for a covering operation the like-shaped central portions 26 of the shell S and 30 of the cover blank B are bonded together congruently.

The manner of folding the cover blank B is similar to that of folding the shell blank. The two blanks are both cruciforms, in the flat; a difference in general shape of the two blanks is apparent in the corner-lapping tabs of the side-wall-forming parts of the cover blank. Two of these side-wall forming parts, 31 and 32 which are oppositely disposed, are provided with corner-lapping tabs 33 and 34, and 35 and 36, respectively; and for this reason the cover blank has four fold-lines in addition to the eight fold-lines corresponding to the eight fold-lines of the shell blank. These fold-lines of the corner-lapping tabs are designated 37; the other two side-wall-forming parts of the cover blank B as 38 and 39.

To facilitate further reference to the cover blank B, I designate those portions of the side-wall-forming parts 31, 32, 38, and 39 which are to be affixed to the outer sidewalls of the shell S as

31a, 32a, 38a, and 39a, respectively; and those portions of the same parts which are to be affixed to the inner side-walls of the shell S as 31b, 32b, 38b, and 39b, respectively. Any of the four fold-lines along the perimeter of the rectangular central portion 30 is designated 40; and any of the four fold-lines corresponding to the top edge of a side-wall of the shell S is designated 41.

In a covering operation involving a shell S and a cover blank B, the preformed shell is bonded to the central portion 30 of the blank in the usual manner; and the shell, with the cover blank adhering thereto, is placed upwardly against block 41, which enters the shell and serves temporarily as a core therefor.

Now, it will be understood that, as the outer side-walls of the shell are not vertical, but sloping, means ordinarily provided on such box-covering machines for folding upwardly and affixing side-wall-forming parts of cruciform cover blanks to the side-walls of parallelopipedal shells are not suited for use with a shell S and a blank B. For this reason I substitute for the affixing rollers, of which there are four, four modified rollers, all of which are substantially alike. One such roller, i. e., roller 16 (cf. Figs. 1 and 2), is shown separately in Fig. 3.

The structure of any roller 15, 16, 19, or 20 is best understood from a description of how the roller may be made. I prefer to split a tube of suitable length and diameter to form an end-to-end slot 42 therein. In the drawings I designate the unslotted portion of the tube as 43. The outer surface of this portion, as will be seen, operates as a roller surface in affixing the side-wall-forming parts of the cover blank to the shell. The edges of the slot 42 are indexed 44 and 45. I provide two cylindrical end blocks 46 and 47 which are secured within respective ends of the roller and serve as mounts for stub shafts 48 and 49 (see Fig. 3), by means of which the roller, as a whole, may be journaled in one of the usual brackets provided for the stock rollers of box-covering machines of this type.

Within the slot 42 I provide an oscillatory bar 50, pivotally secured to the end blocks 46 and 47 at 51. The bar 50 extends from within the roller through slot 42 and beyond the outer surface of the residual portion 43 of the tube, as shown to best advantage in Figs. 4, 5, and 6. The outer edge of the bar 50, extending lengthwise with respect to the roller, is beveled at 52, the edge 53 between the bevel and a side of the bar being rounded. The bar 50 is normally held proximate to, but not in engagement with, edge 44 of the slot 42, and against detents 54 by means of springs 55. Figs. 4, 5, and 6 are partly in section for the purpose of clarifying the roller structure. A portion of slot 42 is open between edge 44 and the rounded edge 53 at all times; the opening, of course, may be widened by forcing the bar 50 against springs 55.

Each stock roller removed from the machine in applying my attachment thereto is replaced by a roller of the construction described above. The rollers of box-covering machines of this type may be adjustably positioned to accommodate box shells of a great variety of widths and lengths. Obviously, then, the modified rollers of the present attachment may likewise be adjusted to accommodate shells S and blanks B of a great variety of widths and lengths.

These common features of box-covering machines are well-known, form no part of the present invention, and need not be more particu-

larly described. It may be remarked here that the affixing rollers of the unmodified machine are not only mounted so that the two rollers of each opposing pair may be adjustably positioned so as to vary the horizontal distance between the rollers of a pair, but also the brackets of the rollers are each arranged to be rotated upwardly so that the roller may be moved upwardly and out of the path of an ascending, and excessively extending, edge or part of the box structure after the box is complete; also each roller bracket 64 is arranged, as illustrated in Fig. 1, so that the roller thereof is in resilient contact with the box forming elements during part of the covering operation—that is, each roller is normally slightly within the path of the descending plate and the plate itself, as well as parts of the box forming elements, force the rollers of a pair somewhat apart against compression springs provided in the bracket structure.

The foregoing relates particularly to means provided in the attachment of the present invention for folding and affixing side-wall-forming parts of cover blanks. The attachment also includes improved means for folding and affixing the corner-lapping tabs of cover blanks, as mentioned before.

In applying my attachment to the machine I remove the usual metal fingers and supporting brackets provided for this last purpose; and I provide in place of such fingers and brackets a plurality of brushes and brackets of special design.

In Fig. 1 part of the rollers 19, 15, and 20 are cut away so that two of these brushes and parts of their respective brackets may be shown in solid lines. These two brushes are designated 56 and 57; their respective brackets, each mounted on bar 17, are designated 58 and 59. Oppositely disposed to brushes 56 and 57 are another pair, shown in dotted lines in Fig. 1 and in solid lines in Fig. 2, indexed 60 and 61; their respective brackets 62 and 63 are mounted on bar 18. Bars 17 and 18 have been previously described. The brush brackets 58, 59, 62, and 63, are adjustably mounted on these bars so that the brushes of each pair may be positioned to accommodate any of a variety of shells S and blanks B. For example, the brackets 62 and 63, seen in Fig. 2, may be moved nearer to each other on bar 18, or farther away from each other, and fixed in selected positions by means of screws, the heads of which are shown. Each brush is mounted on its related bracket so that the plane of the ends of the filaments of the brush may be varied slightly to conform to sloping side-walls 21 of various shells S. Such obvious adjustments have not been illustrated. The vertical relationship between, say, bar 18 and brushes 60 and 61 and roller 16, illustrated in Fig. 2, is equal to that between bar 17 and brushes 56 and 57 and roller 15. When the bars 17 and 18 are moved toward each other horizontally the brushes engage, fold, and affix the corner-lapping tabs of side-wall-forming parts of the cover blank which have previously been affixed by rollers 15 and 16. To move the bars 17 and 18 together two toggle arms 65 and 66 are provided. The arms 65 and 66 are pivotally mounted to bars 17 and 18 at 67 and 68 respectively. The arms 65 and 66 similarly are pivotally mounted on studs 69 of the activator member 70. When the activator member 70 is moved to the right (by means not shown), the two arms 17 and 18 will move toward one an-

other. This operation is specifically described with respect to blank B subsequently.

With reference, now, to the earlier description of the operation of the unmodified machine with respect to rectangular boxes, I now describe the operation of the machine, with my attachment applied thereto, in covering a shell S with blank B.

Let it be assumed that the blank B is placed within the machine so that the angular disposition of the plan of Fig. 9 conforms to that of the plan of Fig. 1, i. e., so that the four side-wall-forming parts 31, 32, 38 and 39 are respectively parallel to and arranged to be engaged by rollers 15, 16, 19 and 20. Further, that shell S has been placed against block 11, the latter temporarily forming a core therefor; and that the central portion 30 of blank B is congruent with and adhering to the bottom of portion 26 of shell S.

No figure in the drawings illustrates specifically the first folding operation of the side-wall-forming parts of the cover blank, nor of the affixing of the first folded parts; however, the second folding and affixing operation, which is at 90° to, and beneath, the first, but in other respects substantially a functional duplication thereof, is clearly illustrated in Figs. 2, 4, 5, and 6. Thus, to avoid duplication of descriptive matter, the specific description of the operation of a pair of oppositely positioned rollers will be restricted to rollers 19 and 20.

As the machine is set in operation the plunger 12 descends, in the usual manner, carrying downward the block 11, the shell S, and the adhering blank B, until the under surface of the latter contacts the upper surface of the plate 14. Both plungers, 12 and 13, then moving as a unit, carry the plate, blank, shell, and block between rollers 15 and 16, which operation effects folding and affixing of parts 31 and 32 to two opposing side-walls of the shell S, in a manner to be particularly described below.

The side-wall-forming parts 31 and 32 of the blank B are those having at their edges corner-lapping tabs. The two tabs of part 31 are 33 and 34; those of part 32, 35 and 36. After the box-forming elements have been carried down between rollers 15 and 16 the parts 31 and 32 are fixed in position on side-walls of the shell; but the four corner-lapping tabs project beyond the other two adjacent side-walls of the shell. As the bars 17 and 18 are brought toward each other, as a consequence of the normal operation of the box-covering machine, brushes 56 and 57 engage, fold, and affix tabs 33 and 34 of part 31 to side-walls of the shell adjacent to that side-wall thereof upon which part 31 has previously been affixed; and brushes 60 and 61 engage, fold, and affix tabs 35 and 36 of part 32 to side-walls of the shell adjacent to that side-wall thereof upon which part 32 has previously been affixed. An illustration typical of this operation is had in Fig. 8, which shows part 31 folded to accord with its initial machine-fold, and tab 34 folded to accord with its only machine-fold.

Fig. 2 shows, in dotted lines, the position of the box-forming elements during the operation of affixing the corner lapping tabs. In solid lines, in the same figure, the box-forming elements are shown at the beginning of the second side-wall-forming folding and affixing operation. In this figure the near side-wall-forming part 32 has already been affixed to the shell, i. e., that portion of part 32 designated 32a has been so affixed, and that portion designated 32b projects above the

top edge of a sidewall of the shell S. Parts 38 and 39 of the blank B are shown in solid lines in Fig. 2 to have just engaged rollers 19 and 20 respectively. Specifically, the parts 38 and 39 have contacted the edges 52, 52, of the two rollers and the continuing downward movement of the plungers 12 and 13 has effected a slight bend in both parts along fold-lines 40, 40.

In Fig. 2 the edges of the plate 14 are about to contact the edges 44, 44, of the respective slots 42 of rollers 19 and 20. In Fig. 5 this engagement has taken place, as illustrated with reference to roller 19 only, the figure being erased, and roller 20 being omitted.

The engagement between an edge of the plate 14 and an edge 44 of slot 42 of any roller, together with the continuing downward movement of plate 14, operates to rotate the roller. For example, in Fig. 4, where the edges are shown to be in initial contact, with respect to roller 19, it will be seen that plate 14 cannot further descend without effecting rotation of roller 19. In Fig. 4, which is typically illustrative of the beginning of a folding and affixing operation of any roller, it will be seen that part 38 of blank B has engaged and is being folded upwardly by the beveled edge 52 of roller 19. See Fig. 5, wherein a next stage is illustrated; here, as the descent of the plate 14 and of the box-forming elements continues, the roller 19 has continued to rotate, bringing the beveled edge 52 of bar 50 flat against the sidewall 27 of shell S with the part 38, or, strictly, portion 38a thereof, intervening. This figure is illustrative of the moment of actual fixation of a side-wall-forming part of the cover blank.

It has been pointed out that all roller brackets are arranged so that each roller is resiliently held against the box-forming elements during the descent of the latter to insure, as is obvious, positive fixation of the side-wall-forming parts. Also note in Fig. 5 that the bar 50 has rotated on 51 slightly away from detent 53 and against spring 55. This indicates an operative pressure moment which is substantially downward against the side-wall-forming part 38. In Fig. 5 the fold of part 38 along line 40 is complete.

After the operation illustrated in Fig. 5, which specifically shows the second of the folding and affixing operations, all side-wall-forming parts of the cover blank are affixed to the sloping sidewalls of the shell. However, the margins or edges, i. e., 31b, 32b, 38b, and 39b, of the side-wall-forming parts 31, 32, 38, and 39 of blank B now project above the top edges of the side-walls of the shell S.

Thus, the following operation involves the tuck-in or turn-in fingers, previously described. One finger 24 is shown in a position in Figs. 4, 5, and 6 which, with respect to each figure, and the operational stage thereof, is in accordance with the normal operation of the box-covering machine. In Fig. 6 the block 11 has been withdrawn from the shell S, the visible finger 24 has moved forward, folded part 38 on line 41, so that portion 38b thereof is horizontally disposed; presently, upon retraction of finger 24 and reentry of the block 11 into shell S all four edges or margins 31b, 32b, 38b, and 39b will be folded into the shell and affixed to the inner surfaces of the side-walls thereof in the normal manner corresponding to the covering of a rectangular box shell.

Thereafter the box, complete, is ejected from the machine. When the box having the shape of shell S is ejected its upward movement operates to reengage all rollers, but inasmuch as each is

free to move upward and away from the edges of the box and plate 14, the two may pass by merely rotating slightly the respective brackets of the four rollers.

5 I claim:

1. Means for folding and affixing to the sidewall of a box shell sloping with respect to the bottom thereof a side-wall-forming part of a cruciform cover blank adhering to the bottom of said shell, said means comprising a roller having an axial slot therein, and, within said slot, a resiliently and pivotally mounted bar having a beveled edge extending outside said slot, said edge engaging, folding, and affixing said part to said shell as the latter is passed against said roller.

2. In a box covering machine arranged to receive into its covering mechanism a box shell bottom-first, means for folding and affixing to the outside of a box shell having sloping sidewalls side-wall-forming parts of a flat cruciform cover blank adhering to the bottom of said shell, said means comprising a roller having an axial slot therein, an edge of said slot positioned in the path of the advancing box shell so that a bottom edge of said shell engages said edge of said slot and so causes said roller to rotate, and a bar resiliently and pivotally mounted within said slot, an edge of said bar extending outside said slot and being beveled, said edge of said bar folding and affixing such a side-wall-forming part of said cover blank to a sloping sidewall of said shell during rotation of said roller.

3. In a machine wherein a box shell is presented bottom first to be covered with a flat cruciform cover blank adhering to the bottom of said shell, an attachment for adapting the machine to cover a box shell having the external shape of a truncated pyramid comprising two pairs of opposing rollers between which said shell is passed, the first of said pairs being above and disposed at 90° to the second thereof, each roller of said pairs being the means of claim 1.

4. The means of claim 1 in combination with a reciprocating box shell form adapted to have a shell with inwardly sloping sides snugly fitted thereon and to advance the same bottom first past said means arranged in parallelism with a side of said shell.

5. Means for folding and affixing a side-wall covering part of a flat cruciform cover blank against a side of a box shell having the external shape of a truncated pyramid, said means comprising a roller having a longitudinal slot therein, and a beveled impressing bar pivotally and resiliently mounted partly within and partly without said slot, said bar being engaged in passing by a bottom edge of said shell and thereby effecting rotation of said roller and consequent folding and affixing of said part to said side by the tracking of said bar against said part and said side.

6. The means of claim 5 in combination with a reciprocating box shell form adapted to have a shell with inwardly sloping sides snugly fitted thereon and to advance the same, with a cruciform cover blank adhering to the bottom thereof, bottom first into engagement with said means arranged in parallelism with a side of said shell.

7. In combination with the means of claim 5, apparatus for folding and affixing corner-lapping portions of side-wall covering parts of said cover blank to side-walls of said shell adjacent to sidewalls to which the first two of said parts are affixed by the means of claim 5, said apparatus

11

comprising two pairs of oppositely disposed brushes reciprocating in the presence of the partly covered shell in contact with and normal to said side-walls.

MARTIN V. SILBY.
